UNITED STATES PATENT OFFICE.

KONSTANTYN BABECKI, OF WOODSIDE, NEW YORK.

WASH HANGER.

Application filed May 6, 1927. Serial No. 189,327.

This invention relates to improvements in wash hangers, and it is the principal object of my invention to provide a wash hanger apparatus allowing a hanging of the wash from the interior of a building and gradual extension of the clothes line suspending and operating element from the window of a building or taking in of the wash.

Another object of the invention is the provision of a wash hanging apparatus of this type which can readily be attached to any building and removed therefrom, and which is of a comparatively simple and inexpensive construction, yet durable and efficient in its operation.

A further object of my invention is the provision of a wash hanger of this character allowing the suspension of wash or clothes simultaneously from a plurality of lines.

These and further objects and advantages of my invention will become more fully known as the description thereof proceeds, and will then be specifically defined in the appended claims.

In the accompanying drawing forming a material part of this disclosure:

Fig. 1 is a side elevation of the wash hanger constructed according to my invention in place within a suitable chamber formed in the wall of a building partly broken away in order to illustrate the construction clearly. The depending arm of the hanger being adapted to be secured to the outer face of the wall.

Fig. 2 is an end view of my improved wash hanger with the cover for the rope drums removed.

Fig. 3 is a top plan view of my device, partly in section with the rope drums' cover removed, seen in the direction of the arrowed line 3-3 of Figure 1.

Fig. 4 is a cross-section on line 4-4 of Figure 1.

Fig. 5 is a cross-section on line 5-5 of Figure 1.

My device, as illustrated on the drawing consists chiefly of a board 10 or the like to which is attached or integrally made therewith a shorter board 11 arranged at a right angle to board 10. A plurality of brackets or clamps are fastened by bolts and nuts to blocks 12 which are mounted on board 10 and serve to hold a pipe 13 extending longitudinally over the board 10, and in this pipe a rod 14 is movably arranged on rollers 15, so that it can be extended from and carried

back into pipe 13. The pipe 13 is open at the bottom, and a pin 16 extends downwardly through the opening or slot in the bottom of the pipe, and carries at its lower end an eye 17 or the like on which one end of a cord is attached, designated 18. The front end of cord 18 is wound about a roller 19 turning about a stub shaft mounted in a depression at the meeting edge of boards 10 and 11, and is then guided downward in another branch 20 of this depression and over a roller or pulley 21 turning about a shaft journalled in the walls 21' forming said depression. The rope 18 or cord is then guided over the drum 22 to which one end of the rope is secured, while the other end of this cord 18 is then guided back over roller or pulley 21 and roller 19 and is attached to a T-bar 23 near the upper end thereof which is attached to rod 14 near its outer end, and depending therefrom.

In juxtaposition to drum 22 are arranged on the shaft 24 of said drum a drum 25 on one side of drum 22, and drum 26 on the opposite side. The shaft 24 is journalled in suitable bearings on brackets 27, 27' secured to board 11, and carrying at one end a crank 28.

A rope or cord, line or the like 29 is secured at one end to a drum 26 and carried over a roller 30 on a shaft in a slot of board 11 in juxtaposition to roller 21. From this roller the rope is guided through a hole or opening 31 in the head bar of the T-bar 23 and a hole 32 at the other arm of the head bar backward to a roller 33 arranged in a slot of board 11 in juxtaposition to roller 21, the rollers 33, 21 and 30 are provided on one shaft designated 34. The end of rope 29 is then guided over roller 25 or drum, and secured thereto.

A removable cover 35 of the form illustrated in Figure 1, is provided to cover drums 26, 22 and 25 and is locked in place by means of a clamp 36 engaging over the lower edge of the cover when in place while suitable recesses in the side walls of this cover allow the reception of shaft 24 when the cover is in place.

My wash hanging device operates as follows:

When it is desired to hang wash on the line 29 or the two branches of the same, the crank handle is turned inwardly and the rope 18 will draw the rod 14 out of its pipe 15, which will wind the part of rope 18

drawn forward upon drum 21, and pay out the rope 29 with its two branches or portions from the drums 25, 26 until they are fully unwound therefrom and held at their fastening ends. The length of the rope 29 is so selected that at the end of the unwinding movement from the drums 25, 26, the rod will still be partly within its pipe. By turning the crank in the opposite direction, the rope 29 will wind again upon the drums 25, 26, while the other part of rope or cord 18 will wind upon drum 21 and again draw the rope into the pipe, as will be evident from the drawing.

15 It is to be understood that I reserve my right to make such changes in the general arrangement and in the construction of the minor details of my invention as come within the scope of the appended claims without departure from the spirit of the invention.

Having thus described my invention, what I claim as new and desire to secure by Letters Patent is:

25 1. In a wash hanger of the class described, an angular bracket, provided with a plurality of depressions for the reception of the hanger operating elements, a pipe held on the larger horizontal branch of said bracket in the direction of its longitudinal axis, a rod slidably arranged within said pipe, adapted to be extended therefrom, a

T-bar depending from the outer end of said rod, a rope secured at one end to said rod and at its opposite end to said T-bar, means 35 for guiding said rope intermediate its ends, and a drum for winding said rope and unwinding the same therefrom for moving said rope and rod, and a plurality of clothes hanging lines participating in the outward 40 and inward movements of said rod.

2. In a wash hanger of the class described, an angular bracket, having two branches of unequal length, a pipe secured to the larger branch of said bracket in the direction of its longitudinal axis, a rod slidably mounted in said pipe, a T-bar depending from the outer end of said rod, said pipe having a longitudinal slot in its lower face, a pin depending from said rod through the 50 slot thereof, a rope secured at one end to the end of said pin, rollers for guiding said rope intermediate its ends, and a drum over which the rope is guided intermediate its ends, the other end of said rope secured to said T-bar near its upper end, and a means 55 operating said drums for paying out and drawing in a plurality of clothes line simultaneously with the operation of said rod moving out and in said pipe.

Signed at Woodside, in the county of Nassau and State of New York this 5th day of May A. D. 1927.

KONSTANTYN BABECKI.
